(57) **CLAIM**

We claim the ornamental design for a hearing aid retention member, as shown and described.

DESCRIPTION

FIG. 1 is a perspective view of our new design for hearing aid retention member;

FIG. 2 is a right side elevational view thereof; the left side, top and bottom elevational views thereof being identical to said right side elevational view;

FIG. 3 is a front elevational view thereof; and,

FIG. 4 is a rear elevational view thereof.
